(57) CLAIM

The design for the air motor handpiece, as shown and described.

DESCRIPTION

FIG. 1 is a front view of the air motor handpiece;

FIG. 2 is a rear view of the air motor handpiece of FIG. 1;

FIG. 3 is a right side view of the air motor handpiece of FIG. 1;

FIG. 4 is a left side view of the air motor handpiece of FIG. 1;

FIG. 5 is a plan view of the air motor handpiece of FIG. 1;

FIG. 6 is a bottom view of the air motor handpiece of FIG. 1;

FIG. 7 is a perspective view of the air motor handpiece of FIG. 1; and,

FIG. 8 is a referential view of the air motor handpiece of FIG. 1, in a state of use.

The broken lines shown in the drawings form no part of the claimed design.
